(57) **CLAIM**

The ornamental design for a virtualization device, as shown and described.

DESCRIPTION

FIG. 1 is a front, left perspective view of a virtualization device, showing my new design;

FIG. 2 is a right, rear perspective view thereof;

FIG. 3 is a front view thereof;

FIG. 4 is a rear view thereof;

FIG. 5 is a left side view thereof;

FIG. 6 is a right side view thereof;

FIG. 7 is a bottom view thereof; and,

FIG. 8 is a top view thereof.

Within the drawings, the broken lines show unclaimed portions of the virtualization device, and form no part of the claimed design.

1 Claim, 6 Drawing Sheets(56)
